ABSTRACT OF THE DISCLOSURE

Armor sheaths composed of high-pitched, spirally wrapped, metallic wires, commonly called "rod," are conventionally provided on aluminum power line conductors at points of conductor support. Linemen are frequently required to relocate sheaths along a conductor.

The invention provides a hot line tool, operable through the familiar "shotgun," which can be applied from the side to an unbroken conductor, and similarly removed. The tool includes a two-part nose cone having teeth on its working face for digging into, between and beneath the wires of the sheath and, through a to and fro, step by step rotary action, unwinding, separating and detaching the wires of the sheath from the conductor and from one another without cutting the sheath wires. The operation can be performed in a safe, rapid and efficient manner, and without damage to the conductor.

This invention relates to a novel tool for stripping armor sheaths from installed and active power line conductors.

In power line conductors there has been a strong trend in recent years from copper to aluminum. Wherever aluminum is used as the conductor material it is the practice to provide an armor sheath three to four feet long at each point of conductor support. The sheath is composed of a bundle of metallic wires, which are tightly twisted about the conductor into steep-pitched spiral form.

The sheath performs a number of useful functions. It constitutes a tough, relatively rigid connecting means through which the conductor may be tied to a supporting insulator, while avoiding direct, abrading contact between the vulnerable conductor on the one hand and the insulator and/or tie on the other. It serves as a vibration dampener for the conductor. In some installations it is so relied on for reinforcing the conductor at the point of greatest tensile strain as to make a conductor reinforcing core of iron unnecessary.

The twisted wire armor sheath has proved an instrumentality of great worth, but it has the drawback that up to the present time no practical means has been contrived for economically and conveniently removing the armor sheath from the conductor. This is an important drawback, because the occasions requiring the removal of armor sheaths are numerous.

Frequent line revisions are required by the evergrowing need for expanded service. Old poles rot away and replacement poles must be erected nearby before the conductors can be detached from the mounts on the old poles. For the new set-up the old armor sheaths are not properly located. It is impossible to overlap sheaths. The old, and now discarded, sheaths ought not simply to be left in place because they impose an unnecessary physical load on the conductors. Most revisions and repairs are required to be made without interruption of service, so that whatever service is performed upon the conductors must, if at all possible, be hot line work.

At the present time there is no satisfactory way of stripping armor sheaths away. In some instances the old sheaths are left on the conductor, but where overlap

2

would be unavoidable, they must be taken off. A manual tool is commonly used having a bent and sharpened end, and the armor wires on the hot conductor are individually picked at from a distance. The process is tedious and awkward, and the conductor is very likely to be damaged.

5 The primary object of the present invention is to provide a tool whereby wrapped on armor sheaths of the kind referred to can be expeditiously, economically, conveniently and safely removed, and preferably in such condition that the wires composing the sheath can be salvaged for reuse.

10 It is a salient feature that the tool is adapted to be used in conjunction with the familiar "shotgun" on energized, high voltage conductors; i.e., voltages sufficient, at least, to kill or seriously to injure, a lineman.

15 Other objects and advantages will hereinafter appear. In the drawing forming part of this specification,

20 FIG. 1 is a view in side elevation, showing a tool illustrative of the invention and constituting a presently preferred, practical and advantageous embodiment thereof;

25 FIG. 2 is a view of the tool partly in rear elevation and partly in sectional elevation, showing the tool applied to a conductor, the section being taken on the line 2—2 of FIG. 1, looking in the direction of the arrows;

30 FIG. 3 is a view in front elevation of the two-piece nose cone which is designed to engage with and to unwind the armor rods;

35 FIG. 4 is a fragmentary view in side elevation, similar to FIG. 1 but more comprehensive, on a much reduced scale, and somewhat diagrammatic, showing the tool associated with a conductor and with an armor sheath which it has started to unwind;

40 FIG. 5 is a detail view on a larger scale than FIGS. 1 to 3, showing the lower or movable jaw and an adjusting device carried by such jaw for accommodating the tool to conductors of different diameters; and

45 FIG. 6 is a view of the structure of FIG. 5 as viewed from the right of FIG. 5, the scale being the same as that of FIG. 5.

40 The adjusting device of FIGS. 5 and 6 is shown in FIG. 2, but is intentionally omitted from FIG. 1 in order not to obscure other features of FIG. 1.

45 In FIG. 4 a typical power line installation is shown as regards a single conductor 10. The conductor is surrounded by a conventional armor sheath 12, composed of a bundle of conductive wires or rods 14 which, according to convention, are wound into steep-pitched, intertwined, right-hand spirals. The wires are shown in the preliminary stage of being unwound by the novel tool 16. The tool is both slidable to and fro along the conductor 10, and can be turned, in alternation, clockwise and counterclockwise about the conductor as an axis. The operation will be better understood after the tool has been more completely described. For the present it may be noted that the tool

50 16 having been applied to the conductor is moved forward, toward the left from the position in which it is shown in FIG. 4, to place the left hand or working face of a nose cone 22 in engagement with the right end of the sheath 12. The tool is then rotated a fraction of a turn clockwise, as viewed from the right in FIG. 4, to partially unwind the wires 14, withdrawn along the conductor 10 a short distance, turned counterclockwise idly, and again advanced to start a further four motion series of steps like the one just described. This is repeated until the portions of the wires 14 to the right of the insulator 20 are freed. The tool is then removed and applied to the left of the insulator, the same procedure being followed as before. The tool is then taken away, the sheath is detached from the insulator, and the wires 14 are removed with other hot stick control.

55 The conductor 10, having been made independent of the pole 24, cross-arm 26, and insulator 20, can be mount-

ed through a fresh armor sheath, appropriately located, on a fresh combination of pole, cross-arm and insulator.

The nose cone 22 consists of upper and lower separable sections 28 and 30, which can be snugly fitted together as seen in FIGS. 1, 2 and 3, the lines of separation 32 and 34 being plainly indicated in FIG. 3. As shown, the apex angle of the truncated cone is ninety degrees, although this angle could be varied over a substantial range. The sections 28 and 30, when brought together, form a circular opening at the center capable of accommodating comfortably a conductor 10, of the largest diameter for which the particular tool chosen for illustration is designed. It should be noted, however, that, as seen in FIG. 2, the tool is shown associated with a conductor of the smallest diameter for which the particular tool is designed. This point will be dealt with in more detail at a subsequent point. Tools of like structure are designed to cover other conductor size ranges.

The nose cone is provided on its face with a series of evenly spaced, sharp, raised ribs or blades 36. Nine such ribs are shown illustratively, five being on the upper section 28 and four on the lower section 30. The leading or inner ends of the ribs 36 are made sharp to dig into the end of the armor sheath. Each rib is desirably made arcuate in form as shown, and, also as shown, has its leading, inner end disposed in advance of its trailing, outer end. These details are, however, subject to considerable variation within the scope of the invention, so long as the nose cone is adapted effectively to spread and untwist the wires 14. The nose cone at its base or circumference is desirably scalloped between blades, as shown, a feature which increases substantially the effectiveness of the cone in unwinding and separating the wires.

The upper section 28 of the nose cone is desirably made unitary with an upper, generally semi-circular carrying jaw 38, as by welding. The lower nose cone section 30 is similarly made unitary with a lower carrying jaw 40 which has the cross-sectional form of an inverted T. The jaws 38 and 40, when brought together, form an enclosure of restricted but definite size for the conductor 10, which extends for a considerable distance, say half a foot or so, lengthwise of the conductor 10. They cannot bind the conductor, but they do serve to guide the tool for to and fro bodily movement along the conductor and for to and fro rotary movement about the axis of the conductor. The length of the jaws is, to a considerable degree, a matter of choice. It should be noted, however, that long jaws prevent the possible imposing of highly localized lateral strain on the conductor.

At a point intermediate its ends the upper jaw 38 has affixed to it, as by welding, an upper jaw carrier 42. In the same region the lower jaw 40 has affixed to it, as by welding, a lower jaw carrier 44.

The upper jaw carrier 42 has a hollow, downwardly extending, body portion 46, desirably elliptical in cross-section, which is formed with a longitudinal slot 48 in one side of its lower end, and includes at the same side of its upper end an integral projection 50 on which the jaw 38 is carried.

The lower jaw carrier 44 has an elliptical body portion 52 which fits slidably within the body 46 of the upper carrier 42, and is operable lengthwise thereof. The body 52 has integral with it a projection 54 to which the lower jaw 40 is affixed. The projection 54 extends through the slot 48 and is held against rotation by the walls of the slot. The projection 54 is generally wider than the slot 48, but the projection is formed with channels 56 in its opposite sides for slidably receiving the slot walls.

A threaded stem 58, having a ring 60 at its lower end, is provided as part of the upper jaw unit for manipulating the tool as a whole and for adjusting the lower jaw unit, including the carrier 44, relative to the upper carrier 42. The stem 58 has a full diameter portion, the upper end of which is continuously threaded as shown at 62, and is threaded through the body 52 of the lower carrier. The stem 58 is freely rotatable but it is anchored at its upper

end against axial movement relative to the upper carrier 42. For this purpose, the stem 58 is provided with an extreme upper end portion 64 of reduced diameter which passes upward, with substantial clearance, through an opening of the carrier 42. A bushing 66 fills the space between the circumference of the carrier opening and the stem 58. A washer 68 rests on the shoulder of the stem 58 formed at the junction of the full diameter and the reduced diameter portions of the stem, bearing upward against the upper end of the elliptical chamber formed in the upper carrier body. The protruding, reduced upper end 64 of the stem 58 is threaded. A nut 69 is screwed onto the stem 58 far enough to retain the parts, with freedom for rotation, in the relative positions in which they are shown in FIG. 2, and is so retained by a pin 70. The pin 70 is driven through the nut 69 and through the reduced upper end 64 of the stem 58. The lower end of the upper carrier body 46 is closed by a bushing 72, the bushing being fixed in place by a set screw 73 and forming a bearing for the stem 58. The bushing is desirably made long and narrow so that it can be received in one of the crossing slots of the shotgun.

It will be apparent, assuming a right hand thread 62, that a clockwise rotation of the stem 68 carries the lower jaw 40 away from and clear of the upper jaw 38, at the same time separating the lower section 30 of the nose cone 22 from the upper section 28 thereof. This makes it possible, through the use of a shotgun, to hang the tool on the conductor 10 with the hollow upper jaw 38 supporting the tool. The lower jaw can then be closed on the upper, by manipulating the shotgun to rotate the stem 58, the sections of the nose cone being brought back together by the same action. The tool can now be manipulated by the shotgun to give it the four motion feed already described, for stripping the sheath progressively from the conductor.

The point cannot be over-emphasized that this tool is adapted and intended for hot line work in stripping conductive wire sheaths from intermediate portions of conductors, and that every manipulative step described can be executed with safety and finesse through the conventional, insulating shotgun.

It is not necessary to provide a distinct tool for every different conductor size. A size adapting device is shown in FIG. 2 and is illustrated on an enlarged scale in FIGS. 5 and 6. the web or T body 74 of the lower jaw 40 is punched outward to provide openings 76, a portion of the outwardly displaced metal being retained and utilized to provide perforated ears 78. Midway between the ears 78 a threaded stud 80, having a steep-pitched thread, projects outward from the outer face of web 74. A circular knurled nut 82 is threaded on the stud 80 and bears outward against the middle of a bowed spring 84. The spring 84 passes through the openings of ears 78, and has its ends received freely in the openings 76 of the web 74. Rotation of the nut to force the center of the spring outward forces the ends of the spring inward as shown in FIG. 5, beyond the inner face of the web 74. The ends of the inner faces of the spring are smoothed out and made concave in order to avoid damage to the conductor 10. As seen in FIG. 2, the inward projection of the spring ends narrows the wire receiving space between the jaws, adapting the tool for use on conductors of reduced diameters. Suitable means are provided for enabling the user to preset the device for the known diameter of the conductor. The presetting is important because this is hot line work.

The outer face of the spring 84 is provided at its middle with an index mark 88, and appropriate index marks designated, respectively, "4," "2" and "1/0" are provided on the outer face of nut 82. Bumps 90, 92 and 94 on the face of the nut 82 cooperate with a dimple 96 on the inner face of the spring 84 for detaining the nut yieldingly in positions corresponding to the several conductor diameters indicated on the face of the nut.

The stud 80 has an outer end portion 86 of reduced diameter which passes freely through a small hole formed

through the spring 84 for limiting lengthwise movement of the spring relative to the stud.

I have described what I believe to be the best embodiments of my invention. I do not wish, however, to be confined to the embodiments shown, but what I desire to cover by Letters Patent is set forth in the appended claims.

I claim:

1. A tool adapted for removing from an intermediate length of a continuous, energized power line conductor, an armor sheath composed of a bundle of steep-pitched, spirally wrapped metallic wires, comprising, in combination,

(a) upper and lower jaw units including, respectively, opposed, elongated upper and lower jaws, which jaws are adapted when brought together, to define a conductor confining but nonclamping enclosure, and interfitting, relatively movable jaw carrying members upon which the upper and lower jaws are, respectively, fixedly carried,

(b) cooperative operating means forming parts of the respective units and constructed and arranged for relative operation to bring the jaws together to define the conductor defining enclosure and to retain them so, or to separate the jaws at will so that the tool can be laterally applied to, and removed from, the conductor, and

(c) a two-piece nose cone having a central conductor receiving opening and having its two complementary sections made unitary, respectively, with the upper and lower jaws, so that the nose cone can be opened and closed along with the jaws, the nose cone pieces including blades or ribs on their working faces, which converge at the smaller end of the cone for engagement with the ends of the sheath wires, the cone blades being adapted under the guidance of the conductor to the gauge into, between and beneath the sheath wire ends and to unwind, expand and separate the intact sheath wires from the conductor and from one another through rotary motion of the tool about the conductor.

2. A tool as set forth in claim 1 in which the nose cone is scalloped between the blades at its outer or larger end.

3. A tool as set forth in claim 1 in which the nose cone blades are curved to present convex leading surfaces with the leading inner ends of the blades in advance of the trailing outer ends of the blades.

4. A tool as set forth in claim 1 in which the means for moving the upper and lower jaws toward and from one another comprises a threaded bore through the lower jaw

carrier, and a rotatable screw threaded through said bore and fixed against bodily movement in, and relative to, the upper jaw carrier.

5. A tool as set forth in claim 4 in which the rotatable screw protrudes downward beyond both said jaw carriers and terminates in a ring adapted to be received in, and to be interlocked with, a conventional shotgun.

6. A tool as set forth in claim 1 in which an adjusting device is carried upon the lower jaw and adapted to project inward more or less beyond said jaw for narrowing the conductor confining space between the closed jaws by different predetermined amounts as required by the known diameter of the conductor upon which the tool is to be used.

7. A tool as set forth in claim 6 in which the adjusting device comprises outwardly displaced perforated ears on the lower jaw, a bowed spring mounted on the outer side of the lower jaw with its ends passed through said ears and located in positions to pass freely through openings formed in said jaw, a threaded stud projecting outward from a mid-portion of the lower jaw, and an adjusting nut threaded on said stud and bearing outward against the inner face of the spring, the construction and arrangement being such that the spring ends are forced inward by outward adjustment of the nut.

8. A tool as set forth in claim 7 in which the bowed spring has a central opening formed through it, and the stud has a reduced outer end which is received in said hole for retaining the spring in the desired, operative association with the lower jaw.

9. A tool as set forth in claim 7 in which the inner face of the spring and the outer face of the nut are formed with interfitting parts for yieldingly detaining the nut in predetermined positions, and suitable indicia are provided on the spring and on the screw head for indicating the conductor gauge or diameter for which each such position is appropriate.

10. A tool as set forth in claim 9 in which the interfitting parts on the spring and the nut consist of a single recess or dimple on the inner face of the spring and a plurality of complementary bumps or projections on the outer face of the nut.
